US00D698099S

(12) **United States Design Patent**
Muhr et al.

(10) **Patent No.:** **US D698,099 S**
(45) **Date of Patent:** **** Jan. 21, 2014**

(54) **HUMMINGBIRD FEEDER**

(75) Inventors: **Jason Muhr**, Warrenville, IL (US);
Brian Povich, South Elgin, IL (US)

(73) Assignee: **Central Garden & Pet Company**,
Walnut Creek, CA (US)

(**) Term: **14 Years**

(21) Appl. No.: **29/429,002**

(22) Filed: **Aug. 6, 2012**

(51) **LOC (10) Cl.** **30-03**

(52) **U.S. Cl.**

USPC **D30/124**; D30/128; D30/127

(57) **CLAIM**

The ornamental design for a hummingbird feeder, as shown and described.

DESCRIPTION

FIG. 1 is a perspective view of a hummingbird feeder in accordance with the present invention;

FIG. 2 is a front elevation view of the hummingbird feeder of FIG. 1;

FIG. 3 is a rear elevation view of the hummingbird feeder of FIG. 1;

FIG. 4 is a right elevation view of the hummingbird feeder of FIG. 1;

FIG. 5 is a left elevation view of the hummingbird feeder of FIG. 1;

FIG. 6 is a top plan view of the hummingbird feeder of FIG. 1; and,

FIG. 7 is a bottom plan view of the hummingbird feeder of FIG. 1.

1 Claim, 5 Drawing Sheets
